CLAIM

The ornamental design for a visor frame for headgear article, as shown and described.

DESCRIPTION

FIG. 1 is a side perspective view of a visor frame for headgear article showing our new design;

FIG. 2 is a front view thereof;

FIG. 3 is a left side elevation view thereof, the right side view being a mirror image;

FIG. 4 is a rear elevation view thereof;

FIG. 5 is a bottom plan view thereof; and,

FIG. 6 is a top plan view thereof.

The details shown in broken lines form no part of the claimed design.
